DESIGN FOR A TEXTILE FABRIC

Daniel W. Farnsworth, New York, N. Y.

Application May 18, 1939, Serial No. 85,066

Term of patent 3½ years

To all whom it may concern:

Be it known that I, Daniel W. Farnsworth, a citizen of the United States of America, residing in New York city, in the Borough of Manhattan, county and State of New York, have invented a new, original, and ornamental Design for a Textile Fabric, of which the following is a specification, reference being had to the accompanying drawing, forming part thereof, wherein the figure is a plan view of a piece of textile fabric showing my new design.

I claim:

The ornamental design for a textile fabric, substantially as shown.

DANIEL W. FARNSWORTH.
